UNITED STATES PATENT OFFICE.

HARRY SPAIN, OF ELMIRA HEIGHTS, NEW YORK.

INKWELL.

1,316,116.

Specification of Letters Patent. Patented Sept. 16, 1919.

Application filed May 7, 1919. Serial No. 295,433.

To all whom it may concern:

Be it known that I, HARRY SPAIN, a citizen of Ukraine, residing at Elmira Heights, in the county of Chemung and State of New 5 York, have invented certain new and useful Improvements in Inkwells, of which the following is a specification.

The primary object of the present invention is to provide an improved form of ink 10 well in which there is provided a neck similar to a bottle construction with tapering grooves upon the inner wall thereof adapted for draining a pen point whereby a greatly reduced stopper engaging portion of said 15 neck will be free of ink.

A further object of the invention is to provide an ink well provided with an up- 20 standing outwardly flaring neck portion, the inner wall of which is provided with taper- 25 ing grooves that terminates adjacent the lower end of the neck whereby the stopper positioned therein alone engages the extreme lower end of the neck and is free from contact with the entire surface of said neck, and 30 further, wherein the stopper is peculiarly constructed to permit the ingress of air to the tapering grooves.

With the above general objects in view, and others that will appear as the nature of 35 the invention is better understood, the same consists in the novel form, combination and arrangement of parts hereinafter more fully described and shown in the accompanying drawing, in which like reference characters 40 indicate corresponding parts throughout the several views,

In the drawing,

Figure 1 is a vertical sectional view of an ink well constructed in accordance with the 45 present invention with the stopper therefor in operative position,

Fig. 2 is a top plan view thereof with the stopper removed, showing the ink draining grooves upon the inner wall of the neck, and 50 their termination adjacent the lower end thereof,

Fig. 3 is a side elevational view, of the ink well shown in Fig. 1, and partly in section with the stopper removed showing the 55 ink draining grooves in the neck thereof,

Fig. 4 is a side elevational view of the stopper and

Fig. 5 is a bottom plan view thereof showing the radial grooves in the top flange of 60 said stopper to permit the passage of air to the grooves in the bottom.

An ink well constructed in accordance with the present invention comprises a body portion 6 preferably of cylindrical construction as indicated and embodying 60 relatively thick walls to prevent breakage thereof, while the central portion 7 constitutes the usual ink well, preferably of tapering or conical form as illustrated. The upper wall 8 of the ink well 65 is provided with a centrally disposed up- standing neck portion 9 having a radial top flange 10 while the inner lower edge 11 of the neck 9 is abruptly formed, substantially at right angles to the top 8 as best illustrated in Figs. 1 and 3. The inner face 12 of the neck 9 is provided with a plurality of 70 symmetrically arranged downwardly tapering grooves 13 extending some distance into the neck 9 and terminating at their lower 75 ends a short distance spaced from the lower end 11 of said neck so that at said lower end, there is an uninterrupted cylindrical neck portion to the bottle which constitutes an air-tight closure to the interior thereof when 80 engaged by the stopper to be presently described.

The improved form of stopper is more clearly shown in Figs. 4 and 5 and includes a conical plug portion 14 carrying a cylin- 85 drical flange 15 that is adapted to rest upon the upper edge of the flange 10 of the bottle neck while a hand grip 16 is formed upon the extreme upper end thereof. The lower face of the flange 15 is provided with a plu- 90 rality of spaced radial grooves 17 that permit the ingress of air therethrough into the tapering grooves 13 as more clearly illustrated in Fig. 1, the lower end of the tapering plug 14 engaging the uninterrupted por- 95 tion 11 of the neck to render the contents of the ink well air-tight.

With the present invention, the draining of a pen point upon completion of its use, is accomplished by passing the same into the 100 groove 13 which will cause the flow of ink from the pen point to said groove and downwardly through said groove to the reservoir 7 in the well so that the only portion of the neck engaged by the stopper, that becomes coated with ink is the extreme lower end 11, while the walls 12 of said neck which engage the stopper throughout their length are free of ink coating. Also, by the provision of the radial grooves 17, air is 105 permitted to circulate freely into the grooves 13 so that any ink that might remain there-

on will be quickly dried by the formation of a thin film and will in no manner interfere with the removal of the stopper 14. The only part of the neck that might become coated with ink and which engages the stopper 14 is the extreme lower end thereof and this surface is so small when compared with the remaining portion of the stopper that any formation of ink thereon will not in any manner cause a serious binding of the stopper within the ink well neck.

What I claim as new is:—

- 15 1. An ink well comprising a receptacle, an outwardly flaring neck carried thereby, the inner wall of said neck having a plurality of downwardly tapering grooves formed therein, and terminating at a point slightly spaced from the lower end of the neck, thereby to present a narrow strip of 20 uninterrupted neck portion, and a conical stopper having a plain stem portion contacting said neck throughout its length, and forming a complete closure at the lower end thereof, an overhanging flange carried by 25 said stopper resting on the upper end of the bottle neck, and having radial grooves

in the bottom face thereof to permit the passage of air to said neck grooves.

2. An ink well comprising a receptacle, an outwardly flaring neck carried thereby, 30 said neck being formed on the inner face thereof with a plurality of downwardly tapering grooves, said grooves terminating at a point spaced upwardly of the lower end of said neck to present an uninterrupted 35 surface at the lower end thereof, and a stopper adapted to be received in said neck engaging the lower end of the bottle neck to form an air-tight closure therefor.

3. An ink well comprising a receptacle, a 40 neck carried thereby, said neck having downwardly tapering grooves formed therein, the grooves terminating a slight distance from the lower end of said neck to present a restricted uninterrupted lower stopper 45 engaging portion for said neck, and a stopper having a solid plug received in said neck, the said stopper being constructed to permit the passage of air into said neck grooves.

In testimony whereof I affix my signature. 50

HARRY SPAIN.
